UNITED STATES PATENT OFFICE.

OSCAR KOPP AND WILLIAM PRESTON, OF PARIS, FRANCE.

EXPLOSION-ENGINE.

SPECIFICATION forming part of Letters Patent No. 674,421, dated May 21, 1901.

Application filed December 22, 1900. Serial No. 40,755. (No model.)

To all whom it may concern:

Be it known that we, OSCAR KOPP, a citizen of the Republic of Switzerland, and WILLIAM PRESTON, a citizen of the Republic of France, both residing at No. 60 Boulevard de Clichy, Paris, in the Republic of France, have invented certain new and useful Improvements in Explosion-Engines, of which the following is a full, clear, and exact specification.

10 In existing motors the throttle-valves are as a rule raised automatically by the suction of the piston-motors, while a shaft with a special tappet independent of the motion-receiving shaft controls the escape-valves. This arrangement has, in motors of great velocity in particular, the inconvenience of many irregularities in the movement occasioned by the failure of the throttle-valves to work or through their insufficient working, the opening taking place too late and the mixture admitted into the cylinder being incomplete. In the arrangement which we have invented and which is the basis of this application not only are these inconveniences entirely removed, but also the throttle-valves and the escape-valves are, the same as the ignition, regulated by one and the same shaft, which is the main driving-shaft. The pistons of the various cylinders are for this purpose coupled 25 by pinions connected to the cranks and meshing with a gear of double dimensions fixed upon the main shaft of the motor, which thus transmits the power and also controls the valve mechanism.

30 Figures 1, 2, 3, and 4 of the annexed drawings represent the application of our invention to a vertical motor of two cylinders. Fig. 1 is a side view. Fig. 2 is a vertical sectional view on line *c f* of Fig. 4. Fig. 3 is a vertical 35 sectional view on line *c d* of Fig. 1. Fig. 4 is a horizontal section on line *a b* of Fig. 1.

Between the two cylinders, at an equal distance from their axial planes, a central main shaft *D* is placed, carrying the fly-wheel *F*. Each of the two connecting-rods *A A'*, joined 45 to the two pistons, is connected with the pin of a crank *B B* or *B' B'*. On the axis of each of these cranks is fixed a pinion *C C'*. The pinions *C* and *C'*, which are similar and are 50 arranged in the same horizontal plane, mesh with a wheel *E*, which is fixed on the main shaft *D* and has double the number of teeth of the pinion. By means of the central main

shaft it is possible to control the whole valve mechanism. For this purpose this shaft carries a small helicoidal pinion *G*, meshing with another pinion *H*, fixed to a shaft *I*, which carries all the cams for the valve mechanism. These cams operate successively and alternatively by means of pushers *K*, the rods of the throttle clack-valves *L* and *L'*, and the escape clack-valves *M* and *M'*. The pinions *G* and *H* have the same number of teeth. At the extremity of the shaft *D*, near the pinion *G* and across from the fly-wheel *F*, is fixed the cam *N* for controlling ignition. With one central shaft controlling thus the whole valve mechanism the regularity of the operation of the valves is perfectly insured, this being complete and occurring exactly at the moment required.

We claim—

1. In combination in a motor, a plurality of cylinders, a main shaft *D*, a gear *E* thereon, pinions *C*, *C'*, of less diameter than the gear *E*, one on each side of the gear, the cranks to which the pinions are connected axially, the pitmen extending from said cranks to the pistons of the cylinders, and valve-controlling mechanism arranged to be driven from the shaft *D* and comprising the helicoidal pinion *G* on the shaft *D*, the shaft *I* having the gear *H* thereon meshing with the helicoidal gear and the cams on the said shaft for operating the valves, substantially as described. 85

2. In combination, the cylinders, the main shaft *D*, extending in a plane between them, a gear on the said shaft, the cranks, one for each cylinder located on each side of said shaft with their axes parallel therewith, the pinions of less diameter than the gear and connected axially to the cranks, a helicoidal gear on the main shaft *D*, a gear *H* meshing therewith, a shaft upon which the shaft *I* is supported, the cams on said shaft *I*, the valves and the connections from said cams to the valves and the pitmen arranged parallel with each other, substantially as described. 95

In witness whereof we have hereunto set our hands in presence of two witnesses.

OSCAR KOPP.
WILLIAM PRESTON.
